UNITED STATES PATENT OFFICE.

WILLIAM BATESON, OF TORONTO, ONTARIO, CANADA, ASSIGNOR TO MARY BATESON AND ROBERT CAREY, OF SAME PLACE.

DOOR-SUPPORTING VISE.

SPECIFICATION forming part of Letters Patent No. 423,719, dated March 18, 1890.

Application filed July 8, 1889. Serial No. 316,775. (No model.)

To all whom it may concern:

Be it known that I, WILLIAM BATESON, builder, of the city of Toronto, in the county of York, in the Province of Ontario, Canada, have invented a certain new and Improved 5 Door-Supporting Vise, of which the following is a specification.

The object of the invention is to design a simple instrument which may be easily carried, readily fixed in position, and which will 10 form an effectual support for a door while being fitted and trueed; and it consists, essentially, of a pivoted clamp provided with a suitable spring and screw and designed to be 15 readily clamped upon a work-table or other suitable support, a stationary centering-finger projecting from the said clamp and having on either side of it an expanding jaw designed to form a vise to grasp and support the door 20 inserted between them, the whole being constructed substantially as hereinafter more particularly explained.

Figure 1 is a perspective view showing my 25 device in operation. Fig. 2 is an enlarged perspective view of the device.

In the drawings, A represents the bottom half of a clamp, and B the upper half, which upper half is pivoted at *a* to the bottom half A. A centering-finger C projects, as indicated, from the bottom half A of the clamp 30 and has a blade formed on its end. On either side of this blade wings *b*, of equal length, project. Two arms D are pivoted on the

clamp A, as shown, and the flaring jaws E, formed on the ends of the arms D, project 35 beyond the end of the centering-finger C. Between the inner ends of the arms D, I place a spring F, designed to hold the inner ends apart.

G is a nut screwed on the end of a bolt passing through the clamps A B. Between these clamps and upon the said bolt I place a spiral spring H.

It will be noticed that my device is portable and may be easily fixed into position, as indicated in Fig. 1. In this case the clamps A B are screwed onto the table I, and the edge of the door J is pushed between the flaring jaws E, the sharpened centering-finger C entering the edge of the door, thus centering 40 it and holding it in position with the assistance of the jaws E, which are actuated by the spring F, as indicated.

What I claim as my invention is—

The clamp A B, provided with a suitable 55 bolt, nut, and spring, in combination with the pivoted arms D, actuated by the spring F, and having flaring jaws E, projecting beyond the centering-finger C, which is fixed to the clamp, as shown, substantially as and for the 60 purpose specified.

Toronto, June 28, 1889.

WILLIAM BATESON.

In presence of—

CHARLES C. BALDWIN,
W. G. MCMILLAN.
